DESIGN FOR A PUSH BUTTON SWITCH

Theodore J. Scofield, Jackson, Mich., assignor to
The Sparks-Withington Company, Jackson,
Mich., a corporation of Ohio

Application October 17, 1938, Serial No. 80,511

Term of patent 7 years

To all whom it may concern:

Be it known that I, Theodore J. Scofield, a citizen of the United States of America, residing in the city of Jackson, county of Jackson, and State of Michigan, have invented a new, original, and ornamental Design for a Push Button Switch, of which the following is a specification, reference being had to the accompanying drawing, forming part thereof.

Figure 1 is a perspective view of a push button switch showing my new design;

Figure 2 is a side elevation thereof, a portion being broken away for convenience of illustration.

Figure 3 is a front or end elevation thereof; and
Figure 4 is a cross sectional view taken on the line 4—4 of Figure 2.

I claim:

The ornamental design for a push button switch, substantially as shown.

THEODORE J. SCOFIELD.
